(57) **CLAIM**

We claim the ornamental design for the structural support element for inflatable articles, as shown and described.

DESCRIPTION

FIG. 1 is a top elevational view of the present invention, the bottom view being the same as the top view.

FIG. 2 is an enlarged orthogonal view of the present invention, the rear orthogonal view being a mirror image thereof.

FIG. 3 is a left elevational side view of the present invention, the right side view being a mirror image thereof.

FIG. 4 is a front elevational view of the present invention; and,

FIG. 5 is a front orthogonal view of a support element which is being attached to an inflatable article. The broken line showing of environmental structure is for illustrative purposes only and forms no part of the claimed design.
